PROCESS AND APPARATUS FOR BAGGING
ASPHALTGrover C. Brown, Montebello, Calif., assignor to
The Patent and Licensing Corporation, New
York, N. Y., a corporation of Massachusetts

Application May 28, 1937, Serial No. 145,223

6 Claims. (Cl. 226—51)

This invention relates to a method of and apparatus for packaging asphalt, pitch and other heat liquefiable materials. The invention more particularly relates to the packaging of such materials in relatively flexible containers, as for example, paper bags.

Proposals have recently been made to adopt paper bags as containers for asphalt in place of, or supplementary to, the wooden or metal barrels long employed for the packaging of this material. Bags for this use present the advantages that they are light in weight, they may be made of any size to accommodate the desired quantity of asphalt, they are readily disposable when their contents have been removed, and they provide a package which is clean and neat and increases the saleability of the product. Furthermore, a quantity of asphalt in bags may be stored in a smaller space than may a similar quantity of asphalt placed in barrels or drums.

The packaging of asphalt or the like in bags has, however, raised certain problems not encountered where barrels or drums are used. Thus in the barrelling of asphalt, the asphalt may be supplied in a molten and freely flowable state and run into open headed barrels or drums placed manually, or otherwise delivered, beneath an asphalt discharge spout. Barrels or drums being self-sustaining need no external support as the asphalt is flowed into them and after being filled and headed, or left unheaded but maintained in an upright position, they may be moved without difficulty to a place of storage where the cooling and solidifying of the asphalt takes place. On the other hand, bags are not self-sustaining and, therefore, their walls must be supported against collapse during the filling and closing operations and, furthermore, the support for the bags must be continued, at least to a substantial extent, until the asphalt therein has cooled and solidified or otherwise deformation, and/or rupture of the bags is likely to occur with consequent danger of injury to workmen, loss of material and other undesirable results.

It is accordingly an object of this invention to provide a method of packaging asphalt, or other heat liquefiable materials, in bags in such a manner that the bags are supported against collapse during the filling and closing operations and support is maintained thereon until their contents have solidified sufficiently to provide a self-sustaining package.

A further object of the invention is to provide a method, as stated above, in which the bags are filled and conveyed to a place of storage in a substantially continuous operation.

A further object of the invention is to provide a suitable apparatus for carrying out the above stated method.

60 The above noted objects are attained accord-

ing to my invention which, briefly stated, resides in the provision of a plurality of bag supporting, openable forms constructed to convey bags in succession from a bag inserting station, through bag filling and closing stations and to a bag discharging station. At the latter station, in accordance with the invention, the forms are opened to discharge the bags, while maintaining support thereon, to a receiving means through which the bags are transferred without substantial deformation and with a minimum of manual effort to carrying devices which, in effect, provide a second form to hold and support the bag while the same is conveyed to a place of storage, and until the contents thereof have cooled and solidified.

In the filling of bags or the like with heat liquefiable substances by use of the method and apparatus of the present invention, briefly described above, a continuous operation is obtained, 20 the bags being conveyed successively through the filling and closing stations and to a place of storage and cooling. No direct manual handling of the filled bags is required and the bags are at all times supported to prevent or to minimize danger of deformation or rupture thereof until after their contents have cooled and solidified. Hence the likelihood of injury to the operators, through burns, which might occur if the bags were to be manually handled, or if the bags 30 ruptured and the hot molten contents thereof escaped, is reduced to a minimum. Furthermore the bags with their solidified contents are of a uniform and regular configuration.

For use in the method and apparatus of the present invention, a bag found most suitable comprises one made of 4 plies of kraft paper with the inner ply having its inner surface coated with a suitable material, i. e., clay, which prevents adhesion of the asphalt to the wall of the 40 bag. However, any suitable type of bag may be used in my invention, as for example, substantially impervious cloth bags and the like.

My invention will be more fully understood and further objects and advantages thereof will 45 become apparent when reference is made to the following detailed description and accompanying drawings in which:

Figure 1 is a plan view depicting an apparatus constructed in accordance with the present invention,

Figure 2 is an elevational view of the device shown in Figure 1,

Figure 3 is a sectional view taken on the line 3—3 of Figure 1,

Figure 4 is a view in perspective and on an enlarged scale of a portion of the apparatus of Figures 1 and 2,

Figure 5 is a perspective view of a tote-board 60

preferably employed in the present invention and,

Figure 6 is a perspective view illustrating the manner in which a plurality of the tote-boards 5 with filled bags therein may be stacked.

Referring particularly to Figures 1 and 2, an apparatus embodying the present invention therein and suitable for carrying out my method is disclosed, the apparatus comprising a turn table, indicated generally at 10, and supported thereon to rotate therewith a plurality (4 being shown) of bag supporting and molding forms 20. The apparatus further includes an asphalt supplying means 80, a filled bag receiving chute 40, 10 a conveying system indicated at 50, and a plurality of bag carriers 70, hereinafter referred to as tote-boards.

More specifically describing the several parts of the apparatus the turn table 10 essentially comprises an annular track 11 supported at a suitable height from the floor on legs 12 and an annular ring 13 overlying the track in spaced and rotatable relationship thereto. The ring 13 is provided with a pair of concentric cylindrical flanges 14 secured to the under surface thereof by welding or the like, the flanges having, at spaced points, downwardly extending plates 15. The plates 15 on one of the concentric flanges lie opposite to those on the other of said flanges to provide supporting means for axles 16 extending between opposing plates and secured in a suitable manner in fixed relationship thereto. Rotatably mounted on the axles 16 are wheels 17 adapted to run on the track 11, the mounting 20 of the wheels on the axles preferably comprising an anti-friction bearing such as the ball bearing shown at 18. The annular ring 13 supports on its upper face a plurality of the bag supporting and molding forms 20.

40 The bag supporting and molding forms 20, illustrated in Figures 1, 2 and 4 are constructed of suitable dimensions as to accommodate bags of the desired capacity and comprise a relatively stationary part 20A fixedly secured to the ring 13 and a swingably mounted part 20B pivotally connected to the fixed part 20A. The part 20A preferably comprises a vertically extending plate 21 reenforced along its longitudinal edges as by angle irons 22 and secured, if desired, to the annular ring 13 by welding or the like. Base members comprising angle plates 23 are provided for the part 20A, the angle plates 23 being welded or otherwise secured to the ring 13 and to the lower ends of the angle irons 22. Braces 24 are 50 provided to connect the upper portion of the plate 21 and angle irons 22 with the angle members 23 to maintain the plate 21 in its vertical position. The braces 24 are preferably provided at their upper ends with integral flanges 32 to 60 provide abutments for supporting the arms 30 of a retainer yoke, later described, in a horizontal position.

65 The swingably mounted part 20B of the form essentially comprises a box-like member having one open face and one open end and is hingedly secured to the fixed part 20A. Part 20B, as shown, comprises side members 26, an end member 27 and a face or bottom member 28, all constructed of a suitable material, e. g., sheet steel, 70 and secured together by welding or the like. No reenforcement for this part of the form has been shown, but as will be apparent to one skilled in the art, such reenforcement may readily be provided, e. g., angle irons or the like may be 75 secured along the free edges of the members 26,

27 and 28 to prevent bending or warping of the same, the angle irons preferably being secured to the outer faces of the members. The pivotal connection between the part 20A and part 20B, comprises pintles 25 preferably fixedly secured to the part 20B adjacent the closed corners thereof and extending through bearings provided in the outer ends of angle members 23. An operating handle 29 is provided for the part 20B which may comprise a bar or tube secured to the outer face of the plate 28 parallel and adjacent to the free edge thereof and extending from the side edges of the form a sufficient distance to provide grasping portions. The handle member provides means whereby the part 20B may readily be swung on its pivots from an open position, as shown in full lines in Figure 4, to a closed position, as indicated in dotted lines in said figure and vice versa.

To retain the part 20B in closed position during the supporting of a bag therein from a bag inserting station to a bag discharging station, a retainer yoke is provided which comprises members 30 each pivoted at one of its ends adjacent the upper end of an angle iron 22 and of sufficient length to extend beyond the bottom plate 28 of the part 20B, when the latter is in closed position, to provide a handle. The members 30 are connected by a bar 31 which lies adjacent the bottom plate 28 of part 20B when the latter is in closed position. The retainer yoke provides readily releasable means for positively locking the part 20B in closed position.

At the bag discharge station of the turn table 10, a chute, indicated at 40 is provided which is 35 adapted to receive the open end of the part 20B of each bag supporting and molding form 20 as said part is swung into bag discharging position (see Figure 4). The chute comprises side members 41 and a bottom member 42, preferably constructed of sheet steel or the like, and is supported on a suitable frame-work comprising angle irons 43 and 44. The angle irons 43 each have one of their ends secured to a leg 45 and the other of their ends secured to a channel member 51 of a roller conveyor 50.

The roller conveyor 50 may be of any conventional or suitable construction and, as shown, comprises channel members 51 and rollers 52 supported at a proper elevation from the floor by legs 53. The rolls of the conveyor may be driven, if desired, but preferably the conveyor is supported to extend at a slight angle to the horizontal whereby articles will be carried therealong by the force of gravity. At a point on the conveyor opposite to the lower end of the chute 40, stop means are provided which comprise stop lugs 54 and 55 vertically movable from a raised to a lowered position and vice versa in plates 56 welded or otherwise secured to the side of the conveyor remote from the chute. A suitable operating device is provided to normally maintain the lugs in the raised position but permit them to be lowered when desired. In this construction of the stop lug operating device illustrated, the lugs 54 and 55 each have extending shanks pivotally connected at their lower ends to arms 57 and 58 respectively which are in turn fixed to a shaft 59 rotatably mounted in bearings 60. The arm 58 is extended, at one end, past the shaft 59 and a counter-balance 61 is preferably adjustably mounted on the extended portion. The weight of the counterbalance 61 is such and it is so adjusted on the extending portion of the arm 58 as to normally maintain the stop lugs 54 and 55 75

in their raised position. A foot pedal is preferably provided which may comprise a plate 62 secured by welding or the like to the arm 58 whereby the stop lugs may be retracted to their lowered position against the stop lug lifting action of the counterbalance.

The conveyor 50 is employed to convey tote-boards 70 (see Figures 1, 2 and 5) to the chute 40, where the tote-boards each receive a filled bag of asphalt, and to convey the same away from the chute. Consequently, the arrangement of the stop lugs 54 and 55, conveyor 50, and chute 40 is such that a tote-board may extend lengthwise between the stop lugs and the end of the chute. The chute and roller conveyor are also preferably so placed in relation to the floor that the swingable part 20B of a form 20, when in a discharge position with its outer end lying within one end of the chute 40, slants downwardly in a plane parallel to and slightly spaced from, the plane of the chute bottom, and the lower edge of the bottom plate 42 of the chute is in substantial horizontal alignment with the bag supporting floor of a tote-board on the conveyor 50.

A tote-board, preferably employed in the present invention, is indicated at 70 (see Figures 1, 2 and 5) and comprises a bottom member 71 and upstanding walls 72 forming an open ended and open topped box. Suitable handles are provided to permit ready manual movement of the box, the handles comprising members 73 secured to the walls 72 adjacent their upper edges and extending from the ends of the walls a suitable distance to provide grasping portions. The tote-boards are preferably of wooden construction and the several parts thereof may be secured together by bolts, screws or the like.

The asphalt supplying means indicated in Figures 1 and 2 at 80 comprises a tank 81 preferably provided with steam coils, (not shown), or other suitable means to maintain the material therein in a liquid and freely flowable state. A delivery pipe 82 is provided in communication with the interior of the tank 81 and has a downwardly directed spout located in such position as to overlie the path of the forms 20 as they rotate with the turn table 10. The delivery end of the pipe 82 is provided with a quick acting valve 83 of any suitable type.

In preparation for the filling of paper and other flexible containers according to the method of the present invention and with the apparatus described above, the tank 81 is supplied with asphalt or other heat liquefiable substance to be packaged, the asphalt or the like being maintained in the tank, if necessary by suitable heating means as previously referred to, at such temperatures as to be in a freely flowable state. A supply of empty containers, preferably bags of the type described above, (i. e., 4-ply kraft paper with the inner ply thereof provided with a suitable clay coating to prevent sticking of the asphalt to the paper) is stacked adjacent a station A (see Figure 1). A plurality of the tote-boards are placed on the roller conveyor 50 or adjacent thereto in such a position that they may readily and successively be placed with their bag receiving portions in alignment with the chute 40.

In the carrying out of the method of the present invention, the bag supporting and molding forms 20 have their swingable parts 20B in an open or downwardly swung position as they reach the station A. A bag from the supply thereof is extended by the operator and placed within

the swingable portion of a first form which is then closed and locked in closed position by the retainer yoke 30-31. The turn table is then rotated on the track 11, the rotation of the same being accomplished either manually or by any suitable driving means, until the bag filling form with the open bag therein lies beneath the discharge valve of pipe 82. Rotation of the turn table is then preferably stopped and an operator at a station B (see Figure 1) opens the valve 83 10 to permit a quantity of the asphalt, or other heat liquefiable substance contained in the tank 81, to run into the open bag within the form. At the same time another empty bag is inserted in a second supporting and molding form which has 15 arrived at station A. When the bag is filled to the desired level the operator at station B shuts off the flow from the tank 81, and the turn table is again moved until the first mentioned molding form with its filled bag arrives at station C where 20 the bag is closed and sealed in the closed position by an operator.

The closing and sealing of the bags is preferably obtained by bringing together the upper ends of their lateral walls, and either folding over said 25 walls and stapling them in the folded over position, or stapling a folded capping strip over the gathered bag walls. However, the bags may be closed and sealed in any other desired manner.

While the bag in the first form is being closed and sealed, the bag in the second molding form is filled with asphalt at station B and an empty bag is inserted in a third molding form at station A. The turn table is then again rotated to bring the first mentioned molding form to the 35 discharge station D opposite the chute 40.

The first mentioned filling form with the filled and closed bag therein is opened by an operator who first grasps the handle portions of members 30 of the retainer yoke 30-31 and swings 40 the yoke upwardly. The operator then rotates the portion 20B of the form outwardly by means of the handle 29 until its open end lies within an end of the chute 40 (see Figure 4). When the open end of part 20B is lying within the chute 40, an 45 operator placed at a station E (see Figure 1) grasps the bag lying in the open form by means of suitable tongs or the like and slides it through the chute 40 and onto a tote-board, which was previously placed on the conveyor 50 in alignment with the chute. The tote-board is prevented from sliding across the conveyor as the bag is drawn onto the tote-board by the stop lugs 54 and 55, normally maintained in a raised position by the counterbalance 61 as previously explained. The chute 40 and the tote-boards provide, in effect, forms for additional continuously supporting and molding the filled bags from this point in the operation until their contents have 55 congealed. 60

Thus, it will be noted that from the time each bag is filled and until its contents are cooled and sufficiently congealed, at least one face and both sides of the bag are supported at all times (though seriatim) by the walls of the filling form, the chute and the tote-board, whereby undue distortion of the bag is prevented and the danger of rupture thereof is reduced to a minimum. 70

As the discharging of the bag from the first mentioned filling form is being accomplished, the filled bag in the second mentioned form is being stapled and closed, the bag in the third form is being filled from the tank 81, and an empty 75

bag is being inserted in the fourth form at the station A.

After the tote-board is loaded with the filled bag of asphalt in the manner described, the stop lugs 54 and 55 are withdrawn through depression of the pedal 62 by the operator at station E, and the loaded tote-board is moved down the conveyor 50, preferably by gravity action, and either directly to a storage and cooling point, or to a suitable point from whence it may be conveyed by other means, for example, by a truck or the like, to such cooling and storage point. In the meantime and while the stop lugs are held in their withdrawn position, a second tote-board is preferably brought into alignment on the conveyor with the outer end of the chute 40. The several operations, described above, are repeated until any desired quantity of the asphalt or other heat liquefiable material has been packaged.

At the storage and cooling point, the tote-boards are preferably stacked in superposed relationship as indicated in Figure 6. As will be observed the upstanding walls of the tote-boards prevent compression of the bags by superposed boards, the bags and their contents thus being permitted to cool without deformation or danger of rupture of the bags. The bags, after their contents have solidified, may be removed from the tote-boards and stacked in any suitable manner, the tote-boards being returned to the bag unloading station for further use.

Having thus described my invention in rather full detail, it will be apparent that these details need not be strictly adhered to and that the numerous changes and modifications will suggest themselves to one skilled in the art which come within the scope of my invention as defined in the appended claims.

What I claim is:

1. In an apparatus of the class described, a bag supporting form supported to move in a fixed path, a bag filling means in said fixed path, a conveying means adjacent said fixed path, and means for transferring a filled bag from said supporting form to said conveying means, said transfer means comprising a part of said supporting form and being formed to support the filled bag against deformation during transfer from the supporting means to the conveying means.

2. In an apparatus for the packaging of asphalt in bags, an openable bag supporting form supported to move in a fixed circular path, a bag filling means in said fixed path, a chute adjacent said fixed path and extending in a radial direction with respect thereto, said chute being constructed to receive a portion of the form when the latter is opened, and a conveying means adjacent the chute and extending substantially at right angles thereto.

3. In an apparatus for the packaging of asphalt in bags, a turn table, a plurality of openable bag supporting forms on the turn table, a discharge spout in communication with an asphalt supply and overlying the turn table, a chute adjacent the turn table and extending in a radial direction therefrom, the chute being so constructed and arranged as to receive an openable portion of said forms, and a conveying means adjacent the chute and extending substantially at right angles thereto.

4. In an apparatus for the packaging of asphalt in bags, a turn table supporting thereon a plurality of bag supporting forms, the forms each having a part in fixed position relatively

to the turn table and a part swingably mounted relatively thereto and adapted to be swung from a vertical position to a relatively horizontal position, a discharge spout in communication with an asphalt supply and overlying the turn table, and a chute adjacent the turn table and extending in a radial direction therefrom, the chute being so constructed and arranged as to receive the free end of the swingably mounted part of each said form when said part is in its relatively horizontal position.

5. In an apparatus for the packaging of asphalt in bags, a turn table supporting thereon a plurality of bag supporting forms, the forms each having a part in fixed position relatively to the turn table and a part swingably mounted relatively thereto and adapted to be swung from a vertical position to a relatively horizontal position, a discharge spout in communication with an asphalt supply and overlying the turn table, a chute adjacent the turn table and extending in a radial direction therefrom, the chute being so constructed and arranged as to receive the free end of the swingably mounted part of each said form when said part is in its relatively horizontal position, and a conveying means adjacent the chute and extending substantially at right angles thereto.

6. In an apparatus for the packaging of asphalt in bags, a turn table supporting thereon a plurality of bag supporting forms, the forms each having a part in fixed position relatively to the turn table and a part swingably mounted relatively thereto and adapted to be swung from a vertical position to a relatively horizontal position, a discharge spout in communication with an asphalt supply and overlying the turn table, a chute adjacent the turn table and extending in a radial direction therefrom, the chute being so constructed and arranged as to receive the free end of the swingably mounted part of each said form when said part is in its relatively horizontal position, a conveying means adjacent the chute and extending substantially at right angles thereto, and advanceable and retractable stop means adjacent said conveying means and opposite to the chute.

7. In an apparatus of the class described a turn table, a plurality of bag supporting forms on said turn table for rotation therewith, each of said forms comprising a part mounted in a fixed position on the turn table and forming a vertical wall of said form, and a box-like part having one open end swingably mounted on said turn table between vertical and relatively horizontal positions; and a chute adjacent the turn table and extending in a radial direction therefrom, the chute being so constructed and arranged as to receive the open end of the said swingably mounted part.

8. In an apparatus of the class described a turn table, a plurality of bag supporting forms on said turn table for rotation therewith, each of said forms comprising a part mounted in a fixed position on the turn table and forming a vertical wall of said form, and a box-like part having one open end swingably mounted on said turn table between vertical and relatively horizontal positions; a chute adjacent the turn table and extending in a radial direction therefrom, the chute being so constructed and arranged as to receive the open end of the said swingably mounted part and a conveying means adjacent the chute.
